CONTROL MECHANISM FOR HYDRAULIC
DEVICES

Ralph Erling, Alexandria, Va.

Application April 16, 1934, Serial No. 720,840

7 Claims. (Cl. 60—52)

(Filed but not issued under the act of March 3,
1883, as amended April 30, 1928; 370 O. G. 757)

This invention relates to mechanism for controlling hydraulic devices such as variable delivery pumps, and more especially to means for adjusting parts of the control mechanism to compensate for the reduction in pressure due to wear of parts of the pump.

It is the object of this invention to provide, in control mechanism of the kind mentioned, interconnecting elements that are adjustable to vary the effect upon the stroke of the pump of a given degree of actuation of the control operating means to prevent reduction, by leakage in the pump, of the quantity of fluid delivered per stroke.

In the drawings:

Fig. 1 illustrates one form of the present invention, the pump being shown in section along the axis of rotation thereof;

Fig. 2 is a section through the pump transverse to its axis of rotation;

Fig. 3 is an enlarged detail view of one of the adjustable connecting means;

Fig. 4 shows a hydraulic system wherein is included another form of my invention;

Fig. 5 is a detail view of a form of my invention that utilizes the same principle of adjustment as in Fig. 4 but with more direct connection to the pump controls;

Figs. 6 and 7 are fragmentary plan views showing the interrupted gear in two different positions;

Fig. 8 is a sectional elevation through Fig. 7 on line 8—8.

The invention forming the subject of the present application is in many respects similar to the device disclosed in my copending application Serial Number 635,379, filed 29 September, 1932. While my improved mechanism is shown, for purposes of illustration, in connection with a steering gear, it is to be understood that it is equally useful with any type of hydraulic mechanism wherein manually operable means are employed for putting stroke on the pump and a follow-up cooperates therewith to take stroke off the pump after the mechanism driven thereby has reached the desired position. It is to be further understood that while one form of the present invention is disclosed as a control for the radial piston type of variable delivery pump, and another form in connection with an axial piston pump, equally satisfactory results will be had from either control apparatus if used with either type of pump.

The rudder post 9 is connected by means of tiller 10 to ram 11 which has its opposite ends disposed to operate as pistons in cylinders 12 and 13 that are respectively connected to pump 14 by

pipes 15 and 16. Manually operable wheel 17 is connected to sun pinion 18 of differential gear 19 by worm 20, gear 21 and shaft 22. The planet pinions 23 and 24, carried by rotatable arm 95, are meshed with sun pinion 18 and with internal gear teeth in the member 25 of differential 19. A flange 26 on member 25 has in it a depression 33 substantially midway between the teeth 27 on member 25. Sector 28 is mounted at one end on rotatable shaft 29 and has at its other end teeth 30 that may be meshed with teeth 27 on the differential member, the stops 31 being provided to limit the swing of sector 28. A roller 32 is rotatably mounted on the under face of sector 28 adjacent the base of the middle tooth 30 and when the sector and differential are in the neutral position (shown in Fig. 1), the roller lies in depression 33 and so tends to stabilize the parts in that position. However, when member 25 is rotated, the teeth thereon act on the teeth of sector 28 and cause the sector to turn also, the roller 32 rides up on the edge of flange 26 and prevents retrograde movement of the sector until member 25 has been rotated back in the opposite direction to bring depression 33 into such position that the roller can move into it.

A shuttle valve 34 connects cylinder 35 of the torque equalizer mechanism always to the pressure side of pump 14. Slidable in cylinder 35 is a piston 36 which is connected to a guide rod 37 slidable in guide 38. Arms 39 extend outwardly from rod 37 and carry a pivot 40 lying substantially at right angles to the arms. Rods 41 pass through apertures in abutment 42 and are connected to the arms 39 by means of externally threaded sleeves 43 which are retained on the rods by heads 44, loading springs 45 being disposed around the rods 41 between abutment 42 and heads 46 on the rods to restrain piston 36 against outward movement until the pressure due to the pump has risen to a predetermined magnitude. Movement of pivot 40 toward cylinder 35 is limited by contact of the ends of sleeves 43 with abutment 42 and it is therefore apparent that by screwing the sleeves 43 into or out of arms 39, the above mentioned limiting position of pivot 40 will be changed which will have the result, in a manner hereinafter explained, of varying the output of the pump to compensate for leakage due to wear of the pump 50 pistons and cylinders.

A lever 47 having longitudinal slots 48 and 49 adjacent its ends is mounted upon the pivot 40, the arm 50 mounted on shaft 29 extending into the slot 49 and a pin 51 carried by sector 52 that 55

is pivotally mounted on guide 38 being disposed in the slot 48. The teeth 53 on sector 52 are engaged with a pinion 54 on shaft 55 to which is fixed the pinion 56 also, the latter pinion being meshed with a rack 57 connected to piston valve 58 in the servo motor that controls immediately the stroke of the pump 14. Inasmuch as servo motors of this type are well known for the purpose herein mentioned and as the servo forms no part of the present invention, it will not be further described.

An auxiliary pump 59, driven by motor 60 which operates pump 14, supplies fluid under pressure through pipe 61 to actuate the servo motor, any excess of fluid being passed through relief valve 62 to a tank 63 connected to pump 59 by return pipe 64.

Rudder post 9 actuates differential 19 through follow-up mechanism comprising pinions 65, 66, shaft 67, pinions 68, 69 and shaft 70 to which is a fixed arm 95. Upon an extension of shaft 67 is a pinion 71 meshed with pinion 72 that is secured on shaft 73 to which is fixed a rudder angle index 74 movable over an angle scale 75. The wheel angle is shown on the same scale by index 16 on gear wheel 77 that is meshed with gear 78 on shaft 22. The index 16 is disposed to contact adjustable stops 79 to prevent further rotation of wheel 77 when the wheel has been moved to a position that will put the rudder hard over, the springs 80 on the stops serving to augment the effort required to turn the wheel and to warn the helmsman that the hard-over position is being approached. It is to be understood that gear 77 is not connected to shaft 73, but acts independently of the shaft.

When wheel 77 is turned, the differential 19 is acted upon and, since the rudder post and follow-up hold the planet pinions 23 and 24 stationary, the member 25 is compelled to rotate, which swings the sector 28, rotates shaft 29 and, by means of arm 50, swings lever 41 on its pivot. This movement of lever 41 constrains sector 52 to rotate on its pivot and through the teeth 53, gear 54, shaft 55, gear 56 and rack 57 the pump 14 is put on stroke and caused to begin to deliver fluid to one or the other of the cylinders 12 and 13. As soon as ram 11 begins to slide, the follow-up mechanism acts through differential 19 upon sector 28 to swing lever 41 and take stroke off the pump. However, the sector 28 will not be moved until member 25 has been turned sufficiently so to position the depression 33 that roller 32 may move thereinto and simultaneously to engage teeth 27 with teeth 30. It is thus apparent that full stroke is kept on the pump until substantially the end of movement of the rudder and, likewise, that while a relatively small rotation of wheel 77 suffices to put the pump on full stroke, nevertheless, continued turning of wheel 77 in no way affects the operation of the pump except to define the extent of operation of the follow-up necessary to take the stroke off the pump. Since shifting the position of pivot 40 varies the relative length of the lever arms cooperating with sectors 28 and 52, respectively, that position may be changed to increase the stroke put on the pump by a given degree of actuation of wheel 77 to compensate for leakage due to wear of the pump parts.

It will be observed that when the pressure rises to the point that the resistance of springs 45 is overcome, the piston 36 is moved outwardly, the fulcrum 40 of lever 41 is moved away from the center of rotation of arm 50, thereby changing the lever

arm between fulcrum 40 and arm 50 and also between fulcrum 40 and pin 51, whereby the effect upon the pump stroke of any given angular extent of movement of the arm 50 will be made dependent upon pressure conditions in the system. If arm 50 remains in fixed position while the fulcrum shifts, the lever 41 is rotated to change the setting of control spindle 55, thus varying the stroke of the pump to alter the rate of its output and to keep the pressure substantially at the maximum pressure permitted by springs 45. It is obvious that there will be no shifting of the fulcrum except when the pressure is in the vicinity of the predetermined maximum.

The form of my invention shown in Fig. 4 is the same as that above described except for differences in mechanism employed to transmit movement from sector 28 to control spindle 55' and for omission of a torque equalizer from Fig. 4. The shaft 81 upon which sector 28 is carried 20 serves no purpose other than supporting that sector. Extending upwardly from sector 28 is a pin 82 having one end disposed in a slot 83 in lever 84 having a second slot 85 in its other end. A slidably mounted rod 86 has both ends down- 25 turned, the one of them being disposed in slot 85 and the other being disposed in a slot 87 in an arm 88 fixed to control spindle 96. Lever 84 is pivotally carried by a bracket 89 having in it elongated holes 89 through which securing means 30 are passed to fix the bracket to a support, the purpose of elongating the holes being to make provision for shifting the bracket in the direction of the length of lever 84 whereby the effective arms of the lever on opposite sides of its 35 pivot may be changed to vary the degree of actuation of control spindle 55' for any given movement of sector 28 and so to compensate for wear in the pump.

Fig. 5 shows in detail a device for transmitting 40 movement from sector 28 to arm 88 on control spindle 55' which eliminates the sliding rod 86 shown in Fig. 4 by having lever 84 act directly upon a pin 90 secured to arm 88. It is obvious that the sliding rod 86 in Fig. 4 can be connected 45 directly to the piston valve of the servo motor shown in Fig. 1 or connected immediately to the pump elements whereby the stroke is changed.

The invention herein described may be manufactured and used by or for the Government of 50 the United States of America for governmental purposes without the payment of any royalties thereon.

I claim:

1. The combination with hydraulic mechanism 55 that includes a pump having means to control the delivery of fluid thereby, means driven by such delivered fluid, a differential gear device having two input elements and an output element, a follow-up connecting said driven means 60 and one of said input elements, and manual operating means connected to the other input element, of means connecting said output element to said control means comprising a cylinder, means placing said cylinder always in communication with the pressure side of said pump, a plunger operable in said cylinder, a guide for the outer end of said plunger, an abutment member adjacent that end of said cylinder into which said plunger passes, a lever pivotally mounted 70 on said plunger intermediate the ends of said lever, means slidably engaged with the lever connecting an end of said lever to the output element of the differential whereby limited swing 75 may be imparted to said lever by operation of

- said differential, means slidably engaged with the lever connecting the other end of said lever to the said control means, headed spring supporting rods slidable in said abutment, a loading 5 spring on each of said rods between the head thereof and said abutment to restrain outward movement of said plunger, and adjustable means connecting said rods to the plunger to vary the position of the pivot of said lever when the force 10 in said cylinder acting on said plunger is less than the force exerted thereon by said springs.
2. The combination with hydraulic mechanism that includes a pump having means to control the delivery of fluid thereby, means driven by 15 such delivered fluid, a differential gear device having two input elements and an output element, a follow-up connecting said driven means and one of said input elements, and manual operating means connected to the other input element, 20 of means connecting said output element to said control means comprising a cylinder, means placing said cylinder always in communication with the pressure side of said pump, a plunger operable in said cylinder, a guide for the outer end of 25 said plunger, an abutment member adjacent that end of said cylinder into which said plunger passes, a lever pivotally mounted on said plunger intermediate the ends of said lever, means slidably engaged with the lever connecting an end 30 of said lever to the output element of the differential whereby limited swing may be imparted to said lever by operation of said differential, means slidably engaged with the lever connecting the other end of said lever to said control means, 35 headed spring supporting rods slidable in said abutment, a laterally extending arm fixed to each side of said plunger, a sleeve on each of said rods adjustably engaged with said arm adjacent thereto and having a face adapted to contact 40 said abutment to limit the movement of said plunger into said cylinder, and a loading spring on each of said rods between a head thereof and said abutment to restrain outward movement of 45 said plunger.
3. The combination with hydraulic mechanism that includes a pump having means to control the delivery of fluid thereby, means driven by such delivered fluid, a differential gear device having two input elements and an output element, 50 a follow-up connecting said driven means and one of said input elements, and manual operating means connected to the other input element, of a lever, a bracket on which said lever is pivotally mounted, said bracket being adjustable longitudinally of the lever on the bracket support, means slidably engaged with the lever connecting one end of said lever to said output element whereby actuation of the output element 55 imparts limited swing to said lever, and a slideable member connected to the other end of said lever and to said control means.
4. The combination with hydraulic mechanism that includes a pump having means to control the delivery of fluid thereby, means driven by 5 such delivered fluid, a differential gear device having two input elements and an output element, a follow-up connecting said driven means and one of said input elements, and manual operating means connected to the other input element, 10 of a lever, a bracket on which said lever is pivotally mounted, said bracket being adjustable longitudinally of the lever on the bracket support, means slidably engaged with the lever connecting one end of said lever to said output element whereby actuation of the output element

imparts limited swing to said lever, and means slidably engaged with the lever connecting the other end of said lever to said control means.

5. The combination with hydraulic mechanism that includes a pump having means to control the delivery of fluid thereby, means driven by such delivered fluid, a differential gear device having two input elements and an output element, a follow-up connecting said driven means and one of said input elements, and manual operating means connected to the other input element, of means connecting said differential to said control means including a torque equalizer having a cylinder connected to receive fluid under pressure from said pump and a plunger 15 slideable in said cylinder, a lever pivotally mounted intermediate its ends upon said plunger, means slidably engaged with the lever connecting one end of said lever to said output element whereby actuation of the differential imparts limited 20 swing to said lever, means slidably engaged with the lever connecting the other end of said lever to said control means, and adjustable means to vary the limit of movement of said plunger into 25 said cylinder.

6. The combination with hydraulic mechanism that includes a pump having means to control the delivery of fluid thereby, means driven by such delivered fluid, a differential gear device having two input elements and an output element, 30 a follow-up connecting said driven means and one of said input elements, and manual operating means connected to the other input element, of means connecting said differential to said control means comprising a lever pivotally 35 mounted intermediate its ends, means slidably engaged with the lever connecting one end of said lever to said output element whereby actuation of the differential imparts a limited swing to said lever, means slidably engaged with the 40 lever connecting the other end of the lever to said control means, and adjustable means to vary semi-permanently the position of the pivot of the lever with respect to both of said connecting means independently of the action of any 45 other parts of the mechanism.

7. The combination with hydraulic mechanism that includes a pump having means to control the delivery of fluid thereby, means driven by such delivered fluid, a differential gear device 50 having two input elements and an output element, a follow-up connecting said driven means and one of said input elements, and manual operating means connected to the other input element, of means connecting said output element to said control means comprising means responsive to pressure in said pump above a predetermined magnitude, means to restrain responsive movement of said pressure responsive means until said pressure reaches said magnitude, a lever 55 pivotally mounted intermediate its ends on an element of said responsive means to be moved translationally therewith, means slidably engaged with the lever connecting one end of said lever to said output element whereby there is imparted to the lever a limited swinging movement when the differential is actuated, means slidably engaged with the lever connecting the other end of 60 said lever to said control means and means adjustable to vary the position of the pivot of said lever with respect to a fixed element of said 65 pressure responsive means.
